UNITED STATES PATENT OFFICE

2,449,460

HEARING AID AND HEAT DEFLECTOR
FOR HAIR DRIERSGeraldine Katharine Edwards, Napoleon, and
Martin Henry Zachrich, Defiance, Ohio

Application December 12, 1946, Serial No. 715,658

4 Claims. (Cl. 34—90)

1

The present invention relates to improvements in hearing aid and heat deflector for hair dryers, and has for an object to provide an improved accessory device for installing in hair drier bells to make it possible for the patron to hear while the drier is in operation, and also serving as a protection to the ears from the heat circulating in the drier.

Another object of the invention is to provide an aid for hearing in which ear shells or trumpets are movably mounted in the hair drier bell in such manner that they may be shifted to a position clear of the ears in the act of mounting and demounting the bell, and which may be adjusted to position fitting over the ears and closely to the side of the head into operative position after the bell has been placed over the head of the patron.

A further object of the invention resides in providing an improved hearing aid for hair dryers in which the movably mounted ear shells are associated with catch devices whereby the same may be held in the retracted positions and freed only after the bell has been finally adjusted to the patron's head.

A still further object of the invention is to provide an improved hearing aid for hair dryers in which the ear shells are carried by simple forms of assemblies adapted to be mounted in any of the conventional types of bells and which may be manufactured and sold at small cost and are so constructed and arranged as not to require expert attention in the mounting of the same in the bells.

A still further object of the invention is to provide a novel form of trumpet or ear shell in which the same is contoured and constructed in a manner most favorable to the picking up of sound waves and directing them into the cavity of the ear.

With the foregoing and other objects in view the invention will be more fully described hereinafter and more particularly pointed out in the appended claims.

In the drawings, in which like parts are denoted by the same reference characters throughout the several views,

Figure 1 is a top plan view of a hair drier bell shown equipped with a hearing aid and heat deflector constructed in accordance with the present invention and with parts broken away and parts shown in section.

Figure 2 is a side elevational view of a hair drier bell shown as adjusted to a patron's head and as equipped with devices according to the

2

invention shown in position adjusted to the ears of such patron.

Figure 3 is an enlarged vertical fragmentary section showing one of the assemblies and its ear shell mounted in place and adjusted to the ear of the patron.

Figure 4 is a similar view showing the ear shell in the retracted and latched position, and

Figure 5 is a perspective view of one of the ear shells.

Figure 6 is a fragmentary side elevational view of a hair drier bell partly broken away and showing a modified form of the invention as in applied position.

Figure 7 is a similar view with the parts shown in the withdrawn position.

Figure 8 is a perspective view of a further modified form of ear shell and support.

Referring more particularly to the drawings 20 10 designates a hair drier bell of a conventional construction and 11 the inner shell of such bell, while 12 represents the bell ring mounted at the lower portion of the bell and converging to the lower opening through which the head of the 15 patron is received as indicated in Figure 2.

Within the inner shell 11 and at opposite sides of the same are detachably mounted assemblies 30 for carrying the two ear trumpets or covers. Such assemblies basically comprise substantially vertical or upright bars 13 fitting up within the inner shell 11 and extending below the same to the lower ends of the bell ring 12. Offsets 14 are produced in the lower portions of the bars 13 and a clamp 15 is formed in the bar below the offset or may be separately formed and affixed to the offset portion of the bar. This clamp has its mouth opening outwardly to permit the same to be slipped over the lower curved edge of the bell ring 12 to which the clamp 15 is secured by 40 a set screw 16.

A bow spring 17 is carried by the bar 13 and extends on the inner side of the same the bow bulging away from the bar inwardly of the shell 11. Rivets or other fastening means 18 may be employed to hold the upper flat end of the spring 17 against the inner wall of the bar 13. Below the bow the spring 17 passes outside the outer wall 19 of the ear shell or trumpet to which it may be affixed by any appropriate fastening, as 50 by example the rivet 20.

The ear shell or trumpet comprises not only the outer wall 19 but also an inner wall 21, the two side walls 22 and the upper closed end 23. Openings 24 and 25 are made respectively in the 55 outer wall 19 and inner wall 21. These openings

are offset vertically, the opening 24 being in the lower portion of the outer wall 19 below the lower edge of the bell ring 12 where such opening 24 is exposed for the reception of sound waves originating in the compartment in which the bell is installed and being employed. The upper opening 25 in the inner wall 21 is above the confines of the lower edge of the bell ring 12 and is positioned to receive the ear of the patron when the bell 10 is adjusted to final position over the head of such patron.

It will be noted more particularly from Figure 5, that the walls of the ear shell or cover are contoured in such manner that from the preferably rounded upper closed end 23 the side walls 22 diverge downwardly and outwardly while the inner and outer walls 19 and 21 also diverge downwardly and outwardly from one another and are also rounded in a gentle curved sweep in a direction away from the inner wall 21. This imparts to the ear shell which is completely open at the larger bottom portion characteristics of a hearing aid or trumpet most suitable to the transmission of sound to the ear of the patron wearing the same.

In Figure 3 the direction of sound waves entering the opening 24 is indicated as impinging upon first the inner wall 21 and then being deflected by the outer wall 19 to the cavity of the ear. The entire ear shell progressively narrows from bottom to top so that the sound waves are thus condensed and funneled to the ear.

The spring 17 may be also conveniently utilized as it is made of resilient metal to form a spring catch 26 upon the lower portion of the same projecting outwardly from the outer wall 19, and below the catch 26 is a cam or terminal end 27 positioned to engage a striker block 28 upon the upper portion of the offset 14. Such striker block is formed with a cam or inclined surface or nose 29 opposed to the cam terminal end 27 of the spring catch. A locking shoulder 30 beyond the inclined surface 29 receives the catch 26 as shown in Figure 4.

In the use of the device, the two ear shells project below the bell 10 and its ring 12 and collects sound waves which are transmitted to the ears of a patron wearing the bell as otherwise the bell covers the ears and closes off the accessibility of sound waves. Figure 2 shows the position occupied by the two ear shells during the period of hair drying. In this position also shown in Figure 3 the ears are allowed to project through the openings 25 and into the internal spaces of the ear shells. The springs 17 are biased to move the shells inwardly or toward one another and to force the same with light pressure against the sides of the head of the patron. Thus the springs 17 both support the ear shells and function to maintain them in place about the ears.

When the drying operation is completed and the bell 10 is to be removed from the head of the patron, the lower projecting portions of the ear shells from suitable handles by which such shells may be engaged and moved outwardly away from the sides of the head of the wearer. In doing so the mutually inclined members 27 and 29 react to cam the spring latch 26 downwardly so that it will spring behind the shoulder 30 and become interlocked therewith. In the interlocked position the ear shells are clear of the ears so that the bell 10 may be lifted from the head without any obstruction. After reinstalling the bell over the head of a subsequent patron, the downwardly projecting portions of the ear shells are grasped

and forcibly moved inwardly to disengage the spring catches 26 from the locking shoulders 30; whereupon the ear shells are released to the influence of the springs 17 which will automatically shift the shells inwardly to a correct hearing position.

It will also be noted that the ear shells form heat deflectors inasmuch as the ear is substantially covered by the shells, the upper portion of the shell being completely closed except for the ear opening 25 and this opening fits all around the side of the head so that the ear is substantially isolated in an enclosed chamber at the upper portion of the ear shell.

It will therefore be appreciated that the invention gives to the patron the free use of the sense of hearing during hair drying operations.

Each assembly may be separate or the bars or frames 13 may be part of a ring fitting around within the inner shell 11 and connecting both ear shell assemblies.

Preferably, however, each bar 13 will be separate to enable the same to be inserted upwardly with its offset 14 and clamp 15 clearing the inner edge of the bell ring 12. Then the clamp may be slipped over the lower edge of the bell ring 12 and in doing so the bar 13 will be moved in place against the inner shell 11. The set screw 16 being tightened the entire device is installed in place. The opposite shell assembly may be mounted in like manner.

The ear shell may be of heat proof plastic material such as Plexiglas, hard rubber, cast aluminum, plastic or other heat non-conducting material.

Referring now to Figures 6 and 7, the bell 10^a supports springs 17^a carrying the ear shells 19^a. These springs 17^a may bias the ear shells 19^a to either the closed position against the ear and head of the wearer of the bell as shown in Figure 6, or to a withdrawn position from the head and ear as at least partially illustrated in Figure 7. It is preferable that the springs 17^a urge the ear shells 19^a inwardly against the head to the position of use shown in Figure 6, in which event a cam or eccentric levers 35 may be employed to exert the necessary pull to draw the ear shells 19^a to the outer position to clear the ears. The levers 35 are fulcrumed at 36 upon fulcrum pins which are slidable in slots formed by the spaced rails 37 welded or otherwise affixed to the sides of the bell 10^a. Arms or links 38 connect the fulcrum pins 36 with the ear shells 19^a. The cam or eccentric curved edges of the levers 35 contact the side wall of the bell 10^a. By lifting the handles of the levers 35 as shown in Figure 7, the cam edge forces the fulcrum pin 36 outwardly in the track 37 and pulls with it the link 38. When the lever 35 is moved to the outermost position, the end of such lever may form a toggle joint with the fulcrum pin 36 and thus lock the ear shell in the outer position. As soon as this toggle lock is broken by the downward swinging movement of the handle of the lever 35 into a small angular distance in a clockwise direction, the spring 17^a will restore the parts to the position shown in Figure 6.

Referring more particularly to Figure 8, the two ear shells 19^b are entirely independent of any hair drier bell but are carried by a piece of spring wire 39 in the form of a yoke looped as at 40 at its central portion and having its free ends connected to hinges 41 upon the outer walls of the ear shells 19^b. In the use of this device the ear shells may be adjusted manually to the sides of the

wearer's head and over the ears in the manner already explained, in which position the spring wire 39 will tend to move the ear shells together and maintain the position, the spring action being enhanced by the loop 40; and the ear shells may individually adjust themselves to a tight position about the ears through the flexibility permitted by the hinges 41.

It is obvious that various changes and modifications may be made in the details of construction and design of the above specifically described embodiment of this invention without departing from the spirit thereof, such changes and modifications being restricted only by the scope of the following claims.

What is claimed is:

1. For use with a hair drier bell or the like, a hearing aid and heat deflector comprising a support mounted within said bell, an ear shell resiliently carried by said support biased by spring pressure against the head of the patron, said ear shell having communication externally of the bell, a spring catch element carried by said shell, and a striker element forming an interlocking couple with said spring catch element and supported from the bell and constructed and arranged for interlocking engagement by the spring catch element when the ear shell is moved to an outer position away from the ear.

2. For use with a hair drier bell or the like, a hearing aid and heat deflector comprising a support mounted within said bell, an ear shell resiliently carried by said support biased by spring pressure against the head of the patron, said ear shell having communication externally of the bell, and an interlocking couple carried between the ear shell and the support for holding the ear shell in outer position away from the ear, said couple comprising a spring catch having a cam terminal end, and a striker block having a cam surface positioned offset said cam terminal end of the spring catch, said striker block also having a locking shoulder back of its cam surface for finally engaging the spring catch.

3. For use with a hair drier bell having inner and outer spaced shells with a bell ring carried by the outer shell, a substantially vertical bar fitted within the inner shell and having an outwardly offset clamp for engaging the lower edge of the bell ring, said bar at its offset portion having a striker block with an inner cam nose and an outer locking shoulder adjoining said nose, a

hollow ear shell adapted to project up within the bell and with a portion extending below the bell, the upper inner portion of the shell having an ear opening, the lower portion of said shell having an open portion to receive sound waves; a bow spring having its upper end affixed to said bar and its lower end affixed to said ear shell, said spring being biased to move the ear shell inwardly against the ear, said spring having a lower portion bent outwardly to form a spring catch for engaging said locking shoulder and a cam terminal end for riding over said cam nose of the striker block.

4. For use with a hair drier bell, a hearing aid and heat deflector comprising an ear shell adapted to fit the ear of the patron wearing the bell, a resilient support in the bell for movably carrying the ear shell and for simultaneously biasing the ear shell to a position about the ear of the patron, said resilient support and said ear shell being so relatively constructed and arranged that portions of the ear shell project up within the confines of the bell and lower portions of the ear shell project below said bell, said ear shell being hollow and comprised of inner and outer walls with a closed top, said ear shell having an ear receiving opening in the upper portion of the inner wall and having an opening in its outer wall extending below the bell and through the bottom of such outer wall, and means for holding the ear shell in an outer position away from the ear.
